SERVICE CONTROL EQUIPMENT

Ralph A. Millermaster and Alex A. Witzmann,
Milwaukee, Wis., assignors to Cutler-Hammer,
Inc., Milwaukee, Wis., a corporation of Delaware

Application June 6, 1938, Serial No. 212,152

19 Claims. (Cl. 200—114)

This invention relates to improvements in service control equipment.

A primary object of the invention is to provide a novel form of service switch device including a fuseless main switch, in combination with range and branch circuit fuses.

Another object is to provide service control equipment wherein the necessity for use of main fuses is eliminated.

10 Another object is to provide a service switch and fusing device of the aforementioned character of extremely compact and inexpensive construction.

15 Another object is to provide a novel form of range fuse pull-out as a part of the combination.

Another and more specific object is to provide for positioning of the range fuses in end to end relationship to each other transversely of the casing which houses the complete device.

20 Another object is to provide for positioning of a plurality of branch circuit fuses in a single row at one side of the range fuses.

Another object is to provide such a device wherein the main switch is positioned at the 25 opposite side of the range fuses from that last mentioned.

Another object is to provide a novel form of enclosing casing including a main cover member having a relatively small opening to provide clearance for and accessibility of the pivoted operating lever of the main switch at the front face of the casing, together with a relatively large opening to provide access to the range and branch circuit fuses.

30 Another object is to provide guard means carried by and cooperating with said main cover member to prevent access to the wiring terminal elements of the device.

Another object is to provide an auxiliary cover member hinged to said main cover member and having novel means to yieldably restrain the same in a position to close said relatively large opening or in a position to provide access through the latter to said range and branch circuit fuses.

40 Another object is to provide novel means on said main and auxiliary cover members to provide for sealing of the latter to the former.

Another object is to provide a range fuse pull-out plug having an operating handle of novel form.

45 Another object is to provide a combination device of the aforementioned character which may be installed in either normal or inverted position, with assurance that the auxiliary cover member will stay open or closed as desired, and wherein

the "on" and "off" indication of the main switch reads correctly in either position of the casing.

Another object is to provide a device of the aforementioned character with means to enable testing of any of the various fuses while in 5 position.

Other objects and advantages of the invention will hereinafter appear.

The accompanying drawings illustrate a preferred embodiment of the invention which will 10 now be described, it being understood that the embodiment illustrated is susceptible of modification in respect of certain structural details thereof without departing from the spirit and scope of our invention as defined by the appended 15 claims.

In the drawings,

Figure 1 is a top plan view of a service control device having the parts thereof constructed and arranged in accordance with our invention,—the 20 main and auxiliary cover members being removed.

Fig. 2 is a bottom plan view of the one-piece molded insulating base showing parts of the switch mechanism and the bus connections between the several parts of the complete device.

Fig. 3 is a bottom plan view of our novel form of range fuse pull-out plug, whereby the range fuses may be mounted in tandem, or end to end, relation.

Fig. 4 is a side elevation of the plug shown in Fig. 3,—with parts broken away and in section to illustrate the manner of attaching the various metal parts to the insulating base of the plug.

Fig. 5 is a fragmentary sectional view, on the line 5—5 of Fig. 1,—the main and auxiliary cover members being shown in assembled relation.

Fig. 6 is a fragmentary sectional view, on the line 6—6 of Fig. 5, showing the parts of the fuseless main switch in circuit interrupting position.

Fig. 7 is a view substantially like that of Fig. 6,—but showing the switch parts in circuit completing position.

Fig. 8 is a detail perspective view (substantially full size) of a stationary part of our improved 45 form of solderless wiring terminal.

Fig. 9 is a bottom plan view (double scale) of the clamping nut for cooperation with the part shown in Fig. 8.

Fig. 10 is a sectional view, on the broken line 10—10 of Fig. 2.

Fig. 11 is a detail perspective view, in separated relation, of certain parts of one of the resilient contacts of the switch.

50

55

Fig. 12 is a diagram showing the circuit connections for the various parts of the complete device.

Fig. 13 is a fragmentary sectional view of a portion of the main cover member and a portion 5 of the auxiliary cover member,—showing the form and arrangement of one of the integral finger lugs formed on the free end of the latter, and

Fig. 14 is a fragmentary sectional view, similar to Fig. 7,—but illustrating a slightly modified 10 form of insulating base to provide therein a downwardly opening bearing slot to receive the pivot pin of the operating lever.

Referring to the drawings, the numeral 15 designates a single molded insulating base adapted 15 to be produced by a straight-line molding operation from a suitable material, such as gray porcelain. Base 15 as shown is of approximately rectangular contour,—except that the corners have been omitted at 16 and 17 to avoid an unnecessary 20 weight or mass of material. Extending transversely of base 15 intermediate the ends thereof (Fig. 1) is a relatively long, outwardly opening, substantially rectangular recess 18, which is adapted to accommodate in a substantially 25 flush relation a correspondingly shaped pull-out plug the molded insulating base of which is designated by the numeral 19. Base 19 is provided with parts, hereinafter described, to receive and retain a pair of cartridge type range fuses in 30 tandem, or end to end, relationship to each other.

Arranged in a line at one side of recess 18, and in a plane offset downwardly from the outer end of the latter (see Fig. 1), is a series of four substantially cylindrical recesses 20, 21, 22 and 23, 35 each of which is respectively adapted to accommodate a screw shell contact 24 and a center contact 25 for cooperation with the screw shell and center contacts of branch circuit fuses of well known form.

40 Arranged at the other side of recess 18, and in a plane offset downwardly slightly below the plane of the upper ends of recesses 20 to 23 (see Fig. 10) is a main switch mechanism,—the insulating operating lever 54 of which projects upwardly a 45 substantial distance beyond the upper end of recess 18. Base 15 is housed within a casing, preferably formed of sheet metal, comprising side walls 27 and 28, end walls 29 and 30, and a bottom wall 31,—to which base 15 is rigidly secured, as 50 by means of a pair of relatively short screws 32, and a pair of relatively long screws, one of which is shown at 33 in Fig. 1. Said pairs of screws 32 and 33 are preferably arranged in the form of a rectangle, as best illustrated in Fig. 2 by the pairs 55 of openings 32^a and 33^a adapted to accommodate the same.

The open front of said casing is provided with a main cover member 34, formed of stamped sheet metal,—said cover member having a peripheral 60 flange which exteriorly overlaps the upper ends of the aforementioned side and end walls, as shown at 35 in Fig. 5. Main cover member 34 is secured to the casing as by means of four screws, one of which is shown at 36 in Fig. 5, which penetrate 65 openings provided at the respective corners of said cover member and take into tapped openings 37 provided in the horizontal arms 38 of brackets, the vertical arms 39 (Fig. 5) of which are welded or otherwise rigidly secured to the 70 opposite ends of side walls 27 and 28.

Main cover member 34 is provided with a relatively large rectangular opening 40 (Fig. 5) which is adapted to provide free access to the recess 18 and to the relatively small cylindrical recesses 20 75 to 23, inclusive. Surrounding opening 40 is a

flange 41 which is offset inwardly from the outer surface of said main cover member,—said flange being adapted to accommodate the auxiliary cover member 42 in a relation substantially flush with said outer surface of said main cover member. 5 Auxiliary cover member 42 is attached to the main cover member as by means of a pair of hinge members of well known form,—one of which is shown at 43 in Fig. 5. Auxiliary cover member 42 is provided near its upper end with an opening 44 10 to accommodate the perforated upstanding lug 45 formed integrally with the aforementioned flange 41. The perforation 46 in said lug is adapted to receive the loop portion of a wire whose ends may be sealed together in the usual manner, to 15 provide for sealing of said auxiliary cover member to said main cover member.

Secured to the inner surface of auxiliary cover member 42 (Fig. 5) at the hinged end of the latter, as by means of a rivet 47, is a resilient plate 20 or spring 48; the fixed end of which is provided with a circular opening to accommodate with a close fit the cylindrical boss or extrusion 49, formed on said auxiliary cover member, whereby 25 turning of plate 48 relatively to rivet 47 is prevented. The free end of plate 48 underlies the adjacent portion of the aforementioned flange 41 and cooperatively engages the inner edge of the latter to yieldably retain the auxiliary cover member 42 in the closed position thereof illustrated. 30 Assuming vertical mounting of the complete device in the manner illustrated in Fig. 5, it is to be understood that plate 48 will cooperate with the edge of flange 41 to yieldably resist a portion of the opening movement of auxiliary cover member 42, whereupon the latter will tend to move by gravity to a fully opened position substantially 35 180 degrees removed from the closed position illustrated.

On the other hand, if the complete device of 40 Fig. 5 is mounted in a vertical position reversed, or upside down, with respect to the position illustrated, plate 48 will cooperate with flange 41 to resist a portion of the opening movement of said auxiliary cover member, and thereafter plate 48 45 will cooperate with the inner edge of flange 41 to hold said auxiliary cover member in a horizontal position affording free access to the aforementioned recesses 18 and 20 to 23. To facilitate opening of the auxiliary cover member 42 we prefer to provide the same, at the end thereof opposite to the hinges, with a pair of integral lugs bent outwardly to arcuate form in cross section,—one of said lugs being shown in elevation at 50 in Fig. 5, and in section in Fig. 13. Also as shown 55 in Fig. 13 the main cover member 34 is provided with non-offset portions 51 of arcuate form which underlie portions of the lugs 50 to minimize the apparent degree of projection of the latter when viewed from the front. A commercial form of 60 our combined main and auxiliary cover members is illustrated in our Design Patent No. 108,212, dated Feb. 1, 1938.

As shown in Figs. 5 to 7 the main cover member 34 is provided with a narrow, elongated depression or offset 52 having formed therein a slot 53 which acts to guide and limit oscillatory movement of the operating lever 54 of the main switch. Underlying the slot 53 is a flat sheet metal plate 55 having an opening formed therein to accommodate 70 date lever 54,—a pair of lugs 56 and 57 being formed integrally with and upstanding from opposite parallel sides of said opening,—the upper ends of said lugs being bent laterally over the bottom wall of depression 52, as shown in Fig. 5, 75

whereby plate 55 is supported by but slideable with respect to said main cover member 34. As shown in Figs. 6 and 7, plate 55 acts to substantially close the aforementioned opening 53 in all positions of the lever 54. Cover member 34 is provided adjacent to the right-hand end of depression 52 with the legend "Off" and at the left-hand end thereof with the legend "On", to indicate the "off" and "on" positions of the main 10 switch (Figs. 6 and 7).

The main switch comprises a relatively narrow substantially rectangular cavity 58 which opens to the lower surface of base 15,—a passage 59 communicating with recess 58 and opening to the upper surface of said base. In assembling the switch mechanism lever 54 is inserted upwardly through passage 59 to an extent sufficient to permit insertion of pin 60 through the pivot opening 61 provided in said lever,—said lever being then lowered to effect seating of pin 60 in the open pivotal bearings 62 and 63 (Fig. 5) provided in the upper surface of base 15. A metal plate 64 overlies the opposite ends of pin 60 to restrain the latter from upward displacement relatively to bearings 62, 63; plate 64 having an opening 65 formed therein to provide clearance for lever 54. Plate 64 is secured to base 15 as by means of a pair of bolts 66 the heads of which are located in countersinks provided in the end wall of recess 30 58 (Figs. 6 and 7).

Lever 54 preferably consists of a flat punched plate of fiber impregnated with a suitable insulating binder material. Any other suitable tough and relatively rigid, fiber reinforced, insulating 35 material may be employed if desired. As best illustrated in Figs. 6 and 7, the lower end portion 54^a of lever 54 extends from the point of pivotal support at an obtuse angle to the upper end portion of said lever,—the arrangement being such 40 that in the "off" position of the switch parts (Fig. 6) said lower end portion 54^a of the lever is in a substantially vertical position with respect to pivot pin 60.

The lower end portion 54^a of said lever is pivotally attached to a substantially rectangular insulating plate 67, at one side of the horizontal and vertical center lines through the latter, as by means of a hollow rivet or eyelet 68. The lower edge of plate 67 is notched or cut away, as indicated at 69, to provide clearance between the same and an insulating barrier plate 70, which is interposed between the sets of cooperating stationary and movable contacts of the switch. As shown in Figs. 6 and 7 the plate 67 is of substantially inverted U-shape,—with the arms thereof projecting to a slight extent below recess 58 in the "on" position of the switch (Fig. 7), while the same project to a greater extent below said recess in the "off" position of the switch 60 (Fig. 6).

Secured to the lower surface of base 15 (Fig. 2) are a pair of substantially rigid stationary contacts 71 and 72 of like form,—the free ends of which underlie, to a very slight extent, the recess 58 (see Fig. 10). Secured to the lower surface of base 15 at the opposite side of recess 58,—and adapted to underlie the latter and portions of contacts 71 and 72, is a pair of resilient contacts 73 and 74 of like form. Contacts 73 and 74 preferably consist of laminations or superimposed strips of resilient conducting material, such as phosphor bronze,—the inner laminations of the respective contacts 73 and 74 having hollow bosses or projections 73^a, 74^a formed thereon (see 74^a in Fig. 10), which bosses are

normally biased into engagement with the respective contacts 71, 72. In Fig. 11 we have shown in perspective the inner lamination 74^b having said boss 74^a formed thereon, together with one of the three other laminations 74^c which we prefer to employ. The initial upward angle provided for the free ends of the laminations like 74^c affords the normal bias of the boss (like 74^a) into engagement with its cooperating stationary contact.

Contacts 73 and 74 are clamped in position against the respective bus members 75 and 76 as by means of bolts 77, 78 and nuts 79, 80,—the heads of said bolts being located in countersinks provided in the upper surface of base 15 (see bolt 15 78 in Fig. 10). Associated with bus member 75 is a bolt 81 (Fig. 2) the shank of which extends upwardly through base 15 and takes into a tapped opening provided in the bottom wall of a channel-shaped wiring terminal element 82 (Fig. 1) to 20 clamp the latter in position. The exposed surface of said bottom wall is provided with a series of alternate grooves and ridges which extend in parallel relation between the side walls of said channel-shaped element, as shown in detail at 25 82^a in Fig. 8.

The threaded shank of bolt 81 preferably extends a substantial distance above the side walls of the channel-shaped element 82 for cooperative engagement by a wire-clamping nut of novel 30 form. As shown in Fig. 9 said nut comprises a lower cylindrical portion 83, the flat lower end of which is provided with a series of concentrically arranged alternate grooves and ridges 35 83^a. By reason of the formation of elements 82 35 and 83 as described we are able to properly clamp a stranded conductor of a size which could not ordinarily be accommodated by known forms of solderless wiring terminals of similar size. A bolt 76^a (Figs. 1 and 2) associated with bus 40 member 76 likewise takes into a tapped opening in the bottom wall of its associated channel-shaped terminal member 82 to clamp the latter in position.

In practice the strands of the wire will be divided, for positioning thereof on opposite sides of the bolt,—whereupon the cylindrical portion 83 of the nut will be screwed home, the slight degree of clearance between portion 83 and the side walls of element 82 being insufficient to permit escape of any of the wire strands, and the surfaces 82^a and 83^a cooperating with the wire strands to insure a proper and efficient electrical engagement. As shown in Figs. 5, 9 and 10 said nut is provided with an upper end portion 83^b of 50 hexagonal or other polygonal contour, to provide for tightening or loosening thereof by means of a suitable wrench,—it being noted (Figs. 5 and 10) that the upper end or head portion 83^b of the nut will always clear the side walls of element 82. 55 Also as shown in Figs. 1 and 10, head portion 83^b is provided with a kerf 83^c to enable adjustment of the nut by means of a screw driver. The screw driver to be employed will preferably have a forked blade, to provide clearance for the shank of a bolt, such as 81 in Fig. 1. We have disclosed use herein of seven solderless wiring terminal units of the character just described, as indicated by the like reference characters applied thereto.

Referring again to Figs. 6 and 7, it will be noted that in the "off" position of the switch the plate 67 abuts at one edge against the left-hand vertical end wall 58^a of recess 58 to insure substantially identical spacing of contacts 73 and 74 70 from the respective stationary contacts 71 and 75

72. Upon a slight degree of counterclockwise movement of lever 54 the resilient contacts 73 and 74 act upon the arms of plate 67 to bias the same upwardly and laterally with a quick action, 5 toward the extreme position thereof shown in Fig. 7, with consequent normal and automatic acceleration of the counterclockwise movement of lever 54.

Referring to Figs. 1 and 10, recess 18 is provided in its bottom wall 18^a along one longitudinal side thereof with four constricted openings,—one pair of which is shown at 18^b and 18^c in Fig. 1,—and one opening of the other pair is shown at 18^d in Fig. 10. Located within suitable recesses (such as recess 84 in Fig. 10) beneath the respective openings are jack receiving contacts of the form illustrated in cross section at 85 in Fig. 10. Each of said contacts preferably consists of a resilient strip of metal, such as 20 phosphor bronze, bent to provide a pair of spaced, upwardly extending parallel arms with outwardly flared ends, and a reflexed connection portion bent laterally to underlie a portion of base 19.

As shown in Fig. 10 the connecting portion of 25 one of said contacts is interposed between the terminal end of stationary contact 72 and base 15,—a bolt 86 having its head located in a countersink in the bottom wall of recess 18 and its threaded shank freely penetrating openings provided in the connecting portion of contact 85 and in the terminal portion of contact 72 and taking into a tapped opening in bus member 87 to clamp said parts in assembled relation. The three other jack receiving contacts, like 85, are 30 secured in position by bolts 88, 89 and 90 (Figs. 1 and 2). Bolt 88 takes into a tapped opening in bus member 91; bolt 89 takes into a tapped opening in bus member 92; and bolt 90 takes into a tapped opening in bus member 93 (Fig. 2). As shown, bus member 92 overlies the terminal end of contact 71 to provide for clamping the latter in position.

The other end of bus member 91 is engaged by the head of bolt 94, the shank of which takes 45 into a tapped opening in the bottom wall of one of the channel-shaped wiring terminal members 82 (Fig. 1). Similarly, the other end of bus member 93 is engaged by the head of bolt 95, the shank of which takes into a tapped opening in the bottom wall of another of the channel-shaped wiring terminal members.

The cartridge type fuse carrying plug comprises the aforementioned insulating base portion 19 having four relatively shallow, substantially rectangular recesses 19^k, 19^l, 19^m and 19ⁿ formed in the inner surface thereof. Each of said recesses is provided substantially centrally thereof with a metal insert in the form of a bolt having a roughened inner end portion 96^a 50 embedded in base 19 for non-rotatable anchorage thereof,—the exposed threaded shank 96^b of each bolt being adapted to penetrate aligned openings provided in the base portions 97^a, 98^a of the jack blade members 97 and the fuse clips 98, respectively. Nuts 99 cooperate with shanks 96^b to clamp members 97 and 98 in assembled 55 position against the bottom wall of a recess (such as 19ⁿ) and against the integral annular extension 96^c formed on each bolt,—spring lock washers 100 (Fig. 4) of suitable form being employed to prevent accidental turning or loosening of said nuts.

As shown, the jacks 97 are arranged adjacent to one longitudinal side of base 19 whereby the same are adapted to register with the aforemen-

tioned constricted openings 18^b, 18^c, etc., in the bottom wall 18^a of recess 18 in only one relative position of the parts.

Base 19 is preferably provided at its mid-length on opposite sides thereof with slight lateral projections 19^a and 19^b, and the opposite longitudinal walls of recess 18 are formed as shown at 18^e and 18^f (Fig. 1) to accommodate said projections,—it being noted that the lower ends (Fig. 4) of projections 19^a, 19^b are of irregular angular contour, as indicated at 19^c, 19^d, and the lateral recesses 18^e, 18^f are correspondingly shaped to insure against insertion of plug 19 into recess 18 in more than one relative position of said parts.

Base 19 is also preferably provided, at a point offset from the mid-length thereof, with an integral barrier member 19^g, which extends downwardly throughout the major portion of the length of jacks 97. The opposite edges 19^h, 19ⁱ 20 of said barrier member extend laterally beyond the projections 19^a, 19^b throughout a portion of the lower ends of the latter,—recess 18 being provided in its longitudinal walls with recesses 18^g, 18^h (Fig. 1) to accommodate said extensions, to 25 additionally limit plug base 19 to insertion in recess 18 in only one relation of said parts. The two longitudinally aligned pairs of clips 98 are adapted to receive and retain a pair of cartridge type fuses for range service.

As shown in Figs. 1 and 10, recess 18 is provided with a barrier 101 formed integrally with the side and bottom walls thereof and extending upwardly from the latter to the degree indicated in Fig. 10, and to provide a seat for the 35 ledge or surface 19^j formed on base 19 (Figs. 3 and 4). By reason of the overlapping relationship of barriers 101 and 19^g, the recess 18 is divided into two compartments effectively sealed electrically with respect to each other prior to 40 engagement of the jack blades 97 with contacts 85. The depth of the peripheral wall of plug base 19 is also preferably such that the upper end of recess 18 is completely sealed off thereby, or made "dead-front" prior to engagement of 45 jack blades 97 with contacts 85.

Plug base 19 is provided with a pair of spaced openings to accommodate the shanks 102^a of a pair of cotter pins whose loops or eyes 102 are exposed at the outer surface of said base, said shanks having their ends spread or bent over washers 103 to retain said cotter pins in position. The handle comprises a length of relatively heavy resilient wire 104, preferably steel, 50 bent to substantially U-shape with laterally extending ends 104^a, 104^b, either of which may be freely inserted into one of the eyes 102, whereupon the other end of said handle may be forcibly inserted into the other eye by a slight degree of bending or distortion of the wire. The arrangement is preferably such that the handle may not be inserted or removed when in upright position, as shown in Fig. 4; but may be readily inserted or removed manually when it is in the inoperative position thereof shown in Fig. 1. This 55 has the advantage of insuring against inadvertent dislocation of the handle in the event of excessive resistance to removal of the fuse carrying plug 19 from recess 18, due to an improper direction of pull upon the handle.

Base 19 is provided with four openings or passages 105, two of which are shown in Fig. 1, which permit access to the base portions of the respective jack blades, as by means of test jacks or wire ends, to permit testing of the range fuses 75

while in position. The branch circuit fuses (not shown) when positioned in the respective recesses 20 to 23, inclusive, may likewise be tested without removal thereof from normal position.—
5 by reason of the provision of angularly extending ways or slots 20^a, 21^a, 22^a and 23^a, which provide access to the respective shell contacts 24, as by means of a test jack,—the wiring terminals 25^a, associated with the center contact screws or bolts 25, being exposed and readily accessible 10 for engagement by the other jack of a fuse testing device of known form, when the main cover member 34 is removed.

As shown in Figs. 1 and 5, the portion 15^a 15 of base 15 in which cylindrical recesses 20 to 23 are formed is preferably offset inwardly from the forward face of the base, as represented by the forward end of the surrounding walls of recess 18. Portion 15^a of base 15 is further provided with an inwardly offset ledge 15^b,—which may be interrupted at a number of points to facilitate proper molding of said base, as shown in Fig. 1. Cover member 34 has attached to the inner surface thereof, as by means of rivets or spot welds, or both (not shown) a sheet metal guard member,—the flat inwardly offset portion 106 (Fig. 5) is shaped to closely surround the contour of the forward end of portion 15^a of base 15,—said flat portion being adapted to seat upon or rest adjacent to the aforementioned ledge 15^b. Guard member 106 is provided with parallel side wall portions, one of which is shown at 106^a,—said side wall portions extending closely adjacent to the surrounding wall of recess 35 18. The rear end wall 106^b associated with guard member 106 completes the enclosure to prevent access to the wiring terminal members of the branch circuit fuses, so long as cover member 34 remains in position.

With the complete device mounted as shown in Figs. 1 and 5, the handle 104 will fall by gravity to the position thereof illustrated, after insertion of plug 19 into recess 18,—the front edge of the lower wall of recess 18 having grooves or 40 notches 18¹, 18² formed therein to accommodate handle 104 in a plane substantially flush with the forward end of the walls of said recess. Handle 104 in such position provides proper clearance for insertion or removal of the branch circuit fuses (see Fig. 1). When the device is mounted in a position 180 degrees reversed from that shown in Figs. 1 and 5, handle 104 may be manually moved to and will remain in the position thereof shown in said figures,—whereby the auxiliary cover member 42 may be closed in the manner aforescribed.

Also as shown in Figs. 1 and 5 a fiber insulating plate 107 of rectangular contour underlies base 15 to insure proper electrical clearance between the conducting parts shown in Fig. 2 and the bottom wall 31 of the metal casing. A grounded neutral bus member 108 is interposed between insulating plate 107 and said bottom wall 31,—the latter having an opening 31^a (Fig. 5) to accommodate the flat cylindrical head 109 of a bolt the threaded shank 109^a of which extends forwardly between the shanks 130 and 131 of a pair of bolts providing additional grounding terminals (Figs. 1 and 2). Said shanks 109^a, 130 and 131 take 65 into tapped openings in the three channel-shaped terminal members 82 (Fig. 1) for cooperation with their associated wire clamping nuts 83^b. Said shanks are electrically connected with each other, as by means of a metal strap or bus member 132 (Figs. 5 and 10).

A second bolt 110 (Figs. 1 and 5) extends rearwardly through base 15 and takes into a tapped opening in bus member 108 to assist in rigidly attaching the latter to said base. Bus member 108 is provided at the lower end thereof 5 (Figs. 1 and 5) with a portion 108^a extending forwardly at a right angle. A neutral terminal member 111 has a right-angled portion 111^a arranged parallel to portion 108^a,—and a bolt 112 has a threaded shank which penetrates portions 111^a and 108^a and takes into a tapped opening in end wall 30 to provide electrical and mechanical connection of said parts to each other and to the metal casing. One end of terminal member 111 overlies a ledge 15^c formed on base 15 to provide against bending or displacement of said member upon tightening of the four binding screws 113 associated therewith. Member 111 may be provided with an opening 111^b to accommodate the bared wired ends to provide a 20 snubbing connection therefor prior to winding or looping the same around the shanks of binding screws 113. As shown in Fig. 2, the branch circuit fuse terminals 25^a are preferably provided with similar openings 25^b to provide snubbing connections for bared wire ends prior to winding or looping the same around the shanks of binding screws 25^c.

In Fig. 12 we have shown diagrammatically the circuit connections for the complete device,—the 30 various parts being designated by numerals corresponding to those employed in the other figures. Thus current is supplied from lines L¹, L² and L³,—the latter being the neutral wire, which is grounded through bus member 108. Upon closure 35 of switch contacts 73 and 74 circuit will be pre-set for completion to the range upon closure of one or more of the usual range switches (not shown),—line L² being thus connected through range fuse 114 with range lead R²; line L¹ being 40 connected through range fuse 115 with range lead R¹; and the grounded neutral L³ being permanently connected with the neutral range lead R³. Closure of contacts 73 and 74 likewise pre-sets the respective pairs of branch circuits 45 116, 117 and 118, 119 for completion to suitable translating devices (not shown) upon operation of suitable switches or plugs associated with the latter,—it being noted that each branch circuit includes therein a grounded neutral connection. 50

In Fig. 14 we have shown an insulating base 120, which is slightly modified with respect to base 15 aforescribed; base 120 being provided with a downwardly opening pair of opposed grooves (one of which is shown at 121) in a passage 122 which 55 opens at one end to the outer surface of base 120 and at its other end communicates with recess 123. A handle member or operating lever 124, having plate 125 pivotally attached thereto at 126, is inserted upwardly through passage 122, 60 with the pivot pin 127 in position in said lever,—pin 127 being adapted to enter the opposed grooves, such as 121, to pivotally bear against the closed upper ends of the latter. When the contacts 73 and 74 are in assembled position they will 65 normally act through engagement thereof with plate 125 to retain pin 127 against displacement from said slots 121. By the arrangement just described, we facilitate assembly of the switch parts, while at the same time obviating the necessity 70 for use of the metal plate 64 and screws 66 shown in Figs. 6 and 7.

The advantages of our invention will be apparent to those skilled in the art. By our novel arrangement the necessity for use of main fuses 75

is obviated,—thus avoiding the principal source of injurious heat in devices of this character. In practice the stationary contacts 11, 12, the part 74^a, 74^b of contact 74, and the corresponding part of contact 73, are provided with a silver electroplate of suitable thickness to insure high current-carrying efficiency of the switch, despite infrequent operation of the latter.

The main switch is operated from the exterior of the casing, with an operating lever like the toggle levers ordinarily employed on switches for home lighting circuits. The familiarity of the ordinary householder with this type of operating means, makes the complete device acceptable and easily understood by the user,—thus resulting in a great reduction in the number of service calls required.

The aforescribed arrangement provides for installation of the complete device in normal position (Figs. 1 and 5) or in an inverted position. In either event the auxiliary cover member 42 stays opened or closed, as desired; and the "on" and "off" indications read correctly. Solid porcelain barriers 128, 129 (Fig. 1) are provided between the solderless terminals associated with the aforementioned sets of bolts 76^a, 95 and 81, 94,—thus preventing the possibility of short circuits.

The jack blades 97 of the range fuse pullout are preferably silver plated, and the same as shown are separate from the respective fuse clips 98,—thus reducing contact temperature to a minimum.

As shown in Fig. 2, the left-hand pair of center contact screws 25, 25 are electrically connected with each other through the medium of bus member 26^a,—which is likewise electrically connected with bus member 87. Similarly, the right-hand pair of center contact screws 25, 25 are electrically connected with each other through the medium of bus member 26^b,—which is electrically connected with bus member 92.

What we claim as new and desire to secure by Letters Patent is:

1. In a service control device, in combination, a metal casing having bottom, side and end walls and an open front, a main cover member, said main cover member having formed therein a relatively large opening, an unfused main switch of the slow-break type positioned within said casing and having an operating member projecting through said main cover member, means comprising a plurality of sets of branch circuit fuse receiving contacts arranged at one side of said switch, a fuse pullout device arranged in parallel relationship to said switch and said sets of branch circuit fuse receiving contacts, said pullout device comprising a plug of substantially rectangular contour, said plug having clips attached thereto to receive and retain a pair of cartridge type fuses, a single molded insulating base adapted to support all of the elements aforementioned, said base having a recess to accommodate said plug, said plug and said sets of branch circuit fuse receiving contacts being readily accessible through said opening, and an auxiliary cover member attached to said main cover member and movable at will with respect thereto to open and close said opening.

2. In a service control device, in combination, a sheet metal casing having bottom, side and end walls and an open front, a main sheet metal cover member, said main cover member having formed therein a slot of relatively small dimensions and a substantially rectangular opening of relatively large dimensions, a one-piece molded insulating base positioned within said casing, a switch mech-

anism supported by said base adjacent to one end of the latter, said switch mechanism having an oscillatable operating member extending outwardly through said slot, a fuse pullout device carried by said base at one side of said switch mechanism in a plane parallel to the plane of oscillation of said operating member, said pullout device including a plug having clips thereon to receive and retain a pair of cartridge type fuses in end to end relationship to each other, four sets of branch circuit fuse receiving contacts arranged in a line at one side of and parallel to said fuse pullout, said fuse pullout and said branch circuit fuse receiving contacts being readily accessible through said relatively large opening, a guard member surrounding portions of said sets of branch circuit fuse receiving contacts to insure against access to the wiring terminal members associated with the latter, and an auxiliary cover member hinged to said main cover member and movable with respect thereto into or out of overlapping relation to said relatively large opening.

3. In a device of the character described, in combination, a molded insulating base having a relatively long substantially rectangular recess formed therein and opening to the front surface thereof, the bottom wall of said recess having a plurality of pairs of openings formed therein, the respective openings being spaced from each other longitudinally of said recess, contacts positioned within the respective openings below the upper surface of said bottom wall, whereby said contacts are concealed, a molded insulating plug member of rectangular contour adapted to fit within said recess to provide for substantially complete closure of the latter, said plug member having jack blades adapted to enter said openings for engagement with the respective contacts, fuse clips electrically and mechanically connected with the respective jack blades, said fuse clips being adapted to receive and retain a pair of cartridge type fuses in end to end relationship to each other, said base having a plurality of relatively small substantially cylindrical recesses formed therein in alignment with each other along one longitudinal side of said first mentioned recess and below the upper surface of the latter, center and screw shell contacts positioned within said cylindrical recesses to accommodate a corresponding number of branch circuit fuse plugs, a switch carried by said insulating base at the other longitudinal side of said first mentioned recess and having an operating member projecting beyond the front surface of said base, a main cover member having a relatively small opening formed therein to provide clearance for said switch operating member and a relatively large opening formed therein to provide access to all of said recesses, and an auxiliary member carried by said main cover member and movable with respect thereto to cover or uncover said relatively large opening.

4. In a device of the character described, in combination, a molded insulating base having a relatively long substantially rectangular recess formed therein and opening to the front surface thereof, the bottom wall of said recess having a plurality of pairs of openings formed therein, the respective openings being spaced from each other longitudinally of said recess, contacts positioned within the respective openings below the upper surface of said bottom wall, whereby said contacts are concealed, a molded insulating plug member of rectangular contour adapted to seat within said recess to provide for substantially

- complete closure of the latter, said plug member having jack blades adapted to enter said openings for engagement with the respective contacts, fuse clips electrically and mechanically connected with the respective jack blades, said fuse clips being adapted to receive and retain a pair of cartridge type fuses in end to end relationship to each other, said base having a plurality of relatively small substantially cylindrical recesses formed therein in alinement with each other along one longitudinal side of said first mentioned recess and below the upper surface of the latter, center and screw shell contacts positioned within said cylindrical recesses to accommodate a corresponding number of branch circuit fuse plugs, a switch carried by said insulating base at the other longitudinal side of said first mentioned recess and having an operating member projecting beyond the front surface of said base, a main cover member having a relatively small opening formed therein to provide clearance for said switch operating member and a relatively large opening formed therein to provide access to all of said recesses, an auxiliary member carried by said main cover member and movable with respect thereto to cover or uncover said relatively large opening, and said main cover member and said auxiliary member being cooperatively formed to provide for attachment of a sealing element thereto.
5. In a device of the character described, in combination, a molded insulating base having a relatively long substantially rectangular recess formed therein and opening to the front surface thereof, the bottom wall of said recess having a plurality of pairs of openings formed therein, the respective openings being spaced from each other longitudinally of said recess, contacts positioned within the respective openings below the upper surface of said bottom wall, whereby said contacts are concealed, a molded insulating plug member of rectangular contour adapted to fit within said recess to provide for substantially complete closure of the latter, said plug member having jack blades adapted to enter said openings for engagement with the respective contacts, fuse clips electrically and mechanically connected with the respective jack blades, said fuse clips being adapted to receive and retain a pair of cartridge type fuses in end to end relationship to each other, said base having a plurality of relatively small substantially cylindrical recesses formed therein in alinement with each other along one longitudinal side of said first mentioned recess and below the upper surface of the latter, center and screw shell contacts positioned within said cylindrical recesses to accommodate a corresponding number of branch circuit fuse plugs, a switch carried by said insulating base at the other longitudinal side of said first mentioned recess and having an operating member projecting beyond the front surface of said base, a main cover member having a relatively small opening formed therein to provide clearance for said switch operating member and a relatively large opening formed therein to provide access to all of said recesses, an auxiliary member carried by said main cover member and movable with respect thereto to cover or uncover said relatively large opening, and said main cover member having a metal guard member attached thereto and offset downwardly therefrom, said guard member being adapted to overlie said insulating base adjacent to said cylindrical recesses to prevent access to wiring terminal members associated
- with the latter when said main cover member is in its assembled position.
6. In a device of the character described, in combination, a molded insulating base having a relatively long substantially rectangular recess formed therein and opening to the front surface thereof, the bottom wall of said recess having a plurality of pairs of openings formed therein, all of the respective openings being spaced from each other longitudinally of said recess, resilient contacts positioned within the respective openings below the upper surface of said bottom wall, whereby said contacts are concealed, a molded insulating plug member of relatively long rectangular contour adapted to seat within said recess to provide for substantially complete closure of the latter, said plug member having jack blades adapted to enter said openings for engagement with the respective contacts, and fuse clips electrically and mechanically connected with the respective jack blades, all of said fuse clips being arranged in longitudinal alinement and the same being adapted to receive and retain a pair of cartridge type fuses in end to end relationship to each other.
7. In a device of the character described, in combination, a one-piece molded insulating base having a relatively long substantially rectangular recess formed therein and opening to the front surface thereof, the bottom wall of said recess having a plurality of pairs of openings formed therein, all of the respective openings being spaced from each other longitudinally of said recess adjacent to one side wall of the latter, resilient contacts positioned within the respective openings below the upper surface of said bottom wall, whereby said contacts are concealed, a one-piece molded insulating plug member of corresponding rectangular contour adapted to fit within said recess in a relationship substantially flush with the front surface of said base to provide for substantially complete closure of said recess, said plug member having jack blades attached thereto and aligned with said openings to enter the latter for engagement with the respective contacts in only one relative position of said plug member and base, fuse clips electrically and mechanically connected with the respective jack blades, all of said fuse clips being arranged in longitudinal alinement and the same being adapted to receive and retain a pair of cartridge type fuses in end to end relationship to each other, and a handle carried by said plug member to facilitate insertion and withdrawal of the latter, said handle being movable to an inactive position substantially flush with the outer surfaces of said plug member and the walls of said recess.
8. As an article of manufacture, a fuse-carrying plug member comprising a molded insulating base of relatively long substantially rectangular contour, two pairs of jack blades arranged in a common plane along one longitudinal side of the inner surface of said base, cartridge type fuse clips associated with the respective jack blades, a bolt and a nut individual to each jack blade and its associated fuse clip for detachably securing the same to each other and to said base, said base having a transverse barrier formed integrally therewith and positioned between said pairs of jack blades and fuse clips, and a lug formed integrally with said base and offset from a median line of the latter, said lug being adapted to cooperate with a recess of suit-

able form to prevent insertion of said plug member in more than one relation.

9. As an article of manufacture, a fuse-carrying plug member comprising a molded insulating base of relatively long substantially rectangular contour, two pairs of jack blades arranged in a common plane along one longitudinal side of the inner surface of said base, cartridge type fuse clips associated with the respective jack blades, means individual to each jack blade and its associated fuse clip for securing the same to each other and to said base, said base having a transverse barrier formed integrally therewith and positioned between said pairs of jack blades and fuse clips, a lug formed integrally with said base and offset from a median line of the latter, said lug being adapted to cooperate with a recess of suitable form to prevent insertion of said plug member in more than one relation, and said insulating base having four test passages formed therein and leading from the outer surface thereof to the respective jack blades, whereby fuses carried by the respective pairs of clips may be tested while said pairs of jack blades are in a normal relation providing for completion of a circuit or circuits controlled thereby.

10. As an article of manufacture, a plug member adapted to receive and retain a pair of cartridge fuses in end to end relationship to each other, said plug member comprising a single molded insulating base of relatively long rectangular contour, said base having four substantially rectangular recesses arranged in longitudinally spaced relation at the inner surface thereof, a corresponding number of bolts having portions embedded in said base and having threaded shanks projecting from the respective recesses, jack blades having base portions bent at substantially right angles thereto and positioned within said recesses, substantially U-shaped clips for ferrule type cartridge fuses, the flat base portions of said clips being positioned within said recesses in superimposed relation to the base portions of said jack blades, said shanks penetrating the base portions of said jack blades and said clips, nuts cooperating with said shanks to clamp said parts in assembled relation, an insulating barrier formed integrally with said first mentioned base and extending transversely between the longitudinally spaced pairs of jack blades and clips, a pair of metal eye members secured to said insulating base and exposed at the outer surface of the latter, and a handle comprising a resilient wire member of substantially U-shape, the arms of which have bent ends which are insertable into and removable from said eye members at will upon bending of at least one of said arms.

11. As an article of manufacture, a plug member adapted to receive and retain a pair of cartridge fuses in end to end relationship to each other, said plug member comprising a single molded insulating base of relatively long rectangular contour, said base having four substantially rectangular recesses arranged in longitudinally spaced relation at the inner surface thereof, a corresponding number of bolts having portions embedded in said base and having threaded shanks projecting from the respective recesses, jack blades having base portions bent at substantially right angles thereto and positioned within said recesses, substantially U-shaped clips for ferrule type cartridge fuses, the flat base portions of said clips being positioned within said recesses in superimposed relation to the base portions of said jack blades, said shanks penetrating the

base portions of said jack blades and said clips, nuts cooperating with said shanks to clamp said parts in assembled relation, an insulating barrier formed integrally with said first mentioned base and extending transversely between the longitudinally spaced pairs of jack blades and clips, a pair of metal eye members secured to said insulating base and exposed at the outer surface of the latter, and a handle comprising a resilient wire member of substantially U-shape, the arms of which have bent ends which are insertable into and removable from said eye members at will upon bending of at least one of said arms, the bent ends of said arms being so related to the outer surface of said insulating base as to substantially prevent removal of the former from said eye members when said handle is in operative position.

12. In a device of the character described, in combination, a metal casing having bottom, side and end walls and an open front, a main cover member removably attached to said casing at the front thereof, said main cover member having a relatively large opening formed therein and an inwardly offset flange surrounding said opening, an auxiliary cover member adapted to seat against said flange in a relation substantially flush with the outer surface of said main cover member, a pair of hinges for connecting said auxiliary cover member to said main cover member at one side of said opening, and a single spring metal strip rigidly secured to the inner surface of said auxiliary cover member between said hinges, said strip cooperating with the edge of said flange at said side of the opening to yieldably retain said auxiliary cover member in its closed or its opened position, said auxiliary cover member when opened providing free access to electrical devices positioned within said casing.

13. In a device of the character described, in combination, a metal casing having bottom, side and end walls and an open front, a main cover member removably attached to said casing at the front thereof, said main cover member having a relatively large opening formed therein and an inwardly offset flange surrounding said opening, an auxiliary cover member adapted to seat against said flange in a relation substantially flush with the outer surface of said main cover member, a pair of hinges for connecting said auxiliary cover member to said main cover member at one side of said opening, a single spring metal strip rigidly secured to the inner surface of said auxiliary cover member between said hinges, said strip cooperating with the edge of said flange at said side of the opening to yieldably retain said auxiliary cover member in its closed or its opened position, said auxiliary cover member when opened providing free access to electrical devices positioned within said casing, and said auxiliary cover member being provided at the edge thereof opposite to said hinges with integral lugs bent outwardly to arcuate form in cross section, to thereby facilitate manual opening of said auxiliary cover member.

14. In a device of the character described, in combination, a metal casing having bottom, side and end walls and an open front, a main cover member removably attached to said casing at the front thereof, said main cover member having a relatively large opening formed therein and an inwardly offset flange surrounding said opening, an auxiliary cover member adapted to seat against said flange in a relation substantially flush with the outer surface of said main cover

- member, a pair of hinges for connecting said auxiliary cover member to said main cover member at one side of said opening, a single spring metal strip rigidly secured to the inner surface of said auxiliary cover member between said hinges, said strip cooperating with the edge of said flange at said side of the opening to yieldably retain said auxiliary cover member in its closed or its opened position, said auxiliary cover member when opened providing free access to electrical devices positioned within said casing, said auxiliary cover member being provided at the edge thereof opposite to said hinges with integral lugs bent outwardly to arcuate form in cross section, to thereby facilitate manual opening of said auxiliary cover member, and said main cover member having non-offset portions of arcuate form underlying said lugs to minimize the apparent degree of projection of the latter when viewed from the front.
15. In a device of the character described, in combination, a metal casing having bottom, side and end walls and an open front, a main cover member removably attached to said casing at the front thereof, said main cover member having a relatively large opening formed therein and an inwardly offset flange surrounding said opening, an auxiliary cover member adapted to seat against said flange in a relation substantially flush with the outer surface of said main cover member, a pair of hinges for connecting said auxiliary cover member to said main cover member at one side of said opening, a single spring metal strip rigidly secured to the inner surface of said auxiliary cover member between said hinges, said strip cooperating with the edge of said flange at said side of the opening to yieldably retain said auxiliary cover member in its closed or its opened position, said auxiliary cover member when opened providing free access to electrical devices positioned within said casing, said auxiliary cover member being provided at the edge thereof opposite to said hinges with integral lugs bent outwardly to arcuate form in cross section, to thereby facilitate manual opening of said auxiliary cover member, said main cover member having non-offset portions of arcuate form underlying said lugs to minimize the apparent degree of projection of the latter when viewed from the front, said main cover member having an integral, upstanding, perforated lug, and said auxiliary cover member having a relatively small opening to accommodate said lug to provide for attachment of sealing means of suitable form.
55. 16. In a service control device, in combination, a metal casing having bottom, side and end walls and an open front, a main cover member, said main cover member having formed therein a relatively large opening, an unfused main switch of the slow-break type positioned within said casing and having an operating member projecting through said main cover member, means comprising a plurality of sets of branch circuit fuse receiving contacts arranged at one side of said switch, a fuse pullout device arranged in parallel relationship to said switch and said sets of branch circuit fuse receiving contacts, said pullout device having an elongated substantially rectangular recess and a plug of corresponding contour adapted to seat therewithin, said plug having clips attached thereto to receive and retain a pair of cartridge type fuses in end to end relationship to each other, a single molded insulating base adapted to support all of the elements aforementioned, said fuse pullout and said sets of branch circuit fuse receiving contacts being readily accessible through said relatively large opening, and an auxiliary cover member attached to said main cover member and movable at will with respect thereto to open and close said relatively large opening.
17. In a service control device, in combination, a sheet metal casing having bottom, side and end walls and an open front, a main sheet metal cover member, said main cover member having formed therein a slot of relatively small dimensions and a substantially rectangular opening of relatively large dimensions, a one-piece molded insulating base positioned within said casing, a switch mechanism of the slow-break type supported by said base adjacent to one end of the latter, said switch mechanism having an oscillatable operating member extending outwardly through said slot, a fuse pullout device carried by said base at one side of said switch mechanism in a plane parallel to the plane of oscillation of said operating member, said pullout device including a plug having clips thereon to receive and retain a pair of cartridge type fuses in end to end relationship to each other, a plurality of sets of branch circuit fuse receiving contacts arranged in a line at one side of and parallel to said fuse pullout, said fuse pullout and said branch circuit fuse receiving contacts being readily accessible through said relatively large opening, said branch circuit fuse receiving contacts being offset inwardly from the forward end of said fuse pullout device, a guard member carried by said main cover member at the inner surface thereof and surrounding portions of said sets of branch circuit fuse receiving contacts to insure against access to the wiring terminal members associated with the latter while said main cover member is in position, and an auxiliary cover member hinged to said main cover member and movable with respect thereto into or out of overlapping relation to said relatively large opening, said auxiliary cover member having a single spring member associated therewith to yieldably resist certain movements thereof in opposite directions respectively.
18. In a device of the character described, in combination, a molded insulating base having a relatively long substantially rectangular recess formed therein and opening to the front surface thereof, said recess being adapted to accommodate a plurality of electric fuses and having means to provide suitable electrical connections for the latter, said base having a plurality of relatively small substantially cylindrical recesses formed therein in alignment with each other along one longitudinal side of said first mentioned recess and below the upper surface of the latter, center and screw shell contacts positioned within said cylindrical recesses to accommodate a corresponding number of branch circuit fuse plugs, a switch carried by said base at the other longitudinal side of said first mentioned recess and having an operating member projecting beyond the front surface of said base, a main cover member having a relatively small opening formed therein to provide clearance for said switch operating member and a relatively large opening formed therein to provide access to all of said recesses, an auxiliary member carried by said main cover member and movable with respect thereto to cover or uncover said relatively large opening, and said main cover member having a metal guard member attached thereto and offset downwardly therefrom, said guard member being adapted to overlie said insulating base adjacent

to said cylindrical recesses to prevent access to wiring terminal members associated with the latter when said main cover is in its assembled position.

- 5 19. In a service control device, in combination, a sheet metal casing having bottom, side and end walls and an open front, a main sheet metal cover member, said main cover member having formed therein a substantially rectangular slot of relatively small dimensions and a substantially rectangular opening of relatively large dimensions, a one-piece molded insulating base positioned within said casing, a fuseless main switch of the slow-break type supported by said base adjacent one end of the latter, said switch having an oscillatable operating member extending outwardly from the front surface of said base, the walls of said slot providing oscillating clearance for said operating member, said base having a plurality of substantially cylindrical recesses formed therein and arranged in a line parallel to the plane of oscillation of said operating member, a set of branch circuit fuse receiving contacts positioned

within each of said recesses, said branch circuit fuse receiving contacts being readily accessible through said relatively large opening, a metal guard member rigidly attached to the inner surface of said main cover member, said guard member having an inwardly offset portion surrounding portions of said branch circuit fuse receiving contacts to insure against access to the usual wiring terminal members associated with the latter while said main cover member is in assembled relation to said casing, an auxiliary metal cover member hinged to said main cover member and movable with respect thereto into or out of overlapping relation to said relatively large opening, and a single sheet metal spring member rigidly attached to said auxiliary cover member and operable with a portion of said main cover member to yieldably retain said auxiliary cover member in its open or its closed position regardless of the mounted position of the complete device. 20
